UNITED STATES PATENT OFFICE.

EDWARD KNAUSS, OF NEW YORK, N. Y.

CARBURETER FOR GASOLENE-ENGINES.

1,304,988.

Specification of Letters Patent. Patented May 27, 1919.

Application filed March 20, 1917. Serial No. 156,054.

To all whom it may concern:

Be it known that I, EDWARD KNAUSS, a citizen of the United States, residing at New York city, in the county of New York, and State of New York, have invented certain new and useful Improvements in Carbureters for Gasolene-Engines; and I do hereby declare the following to be a full, clear, and exact description of the invention, such as will enable others skilled in the art to which it appertains to make and use the same.

This invention relates to carbureters for gasolene and other hydrocarbon engines and has for its object to provide a device of this character which will be comparatively inexpensive to manufacture, simple in construction and more efficient in action than those heretofore proposed.

With these and other objects in view the invention consists in the novel details of construction and combinations of parts more fully hereinafter disclosed and more particularly pointed out in the claims.

Referring to the accompanying drawings forming a part of this specification in which like numerals designate like parts in all the views:—

Figure 1 is an elevational view of a carbureter made in accordance with this invention;

Fig. 2 is a central sectional view of a portion of the parts shown in Fig. 1;

Fig. 3 is an enlarged partially sectional view of the fuel regulating mechanism; and Fig. 4 is a detail sectional view taken on the line 4—4 of Fig. 1, looking in the direction of the arrows.

1 indicates any suitable outer casting or shell provided with the air intake 2 controlled by the air throttle 3, and having the passage 4 connected with the intake of the engine. Fitted to the intake 2 in advance of the throttle 3 is the connection 5 provided with the valve 6. Said connection is joined as at 7 with the pipe 8 adapted to slip into and slip out of the rotating thumb piece 9, as indicated by the slip joint 10', and the said thumb piece 9 is rigidly connected with the tube 10 screw threaded as at 11 and provided with the air delivery end 12.

Surrounding said tube 10 is the tubular feed member 13 having the substantially cylindrical bore at its upper portion and the tapered bore or chamber 14 at or near its lower portion. Rigid with said feed tube 13 is the piston 15 provided with the fuel inlets

16, and surrounding said piston 15 is the tubular member 17 screw threaded at its lower end to accommodate the plug 18 provided with the central screw threaded bore through which the tube 10 passes and also provided with a stuffing box 20 to prevent leakage past said tube 10. The upper end of said member 17 is likewise screw threaded as at 21 to accommodate the outer screw threaded sleeve 22, and said upper end is likewise closed as by the diaphragm member 23 having the hollow extension 24 which accommodates the upper end of the tube 13.

Said tube 13 projects beyond the extension 24 and has rigidly secured thereto as at 25 the perforated diaphragm member 26 having the hollow upwardly projecting extension 27 and the inverted hood member 28 forming the chamber 29 and the narrow passage 30 into which projects the upper end of said extension 27. Rigid with said member 28 and constituting an extension thereof is the flaring mouth like member 31. Between the diaphragm member 23 and the upper surface of the piston 15 is the spring 33 adapted to hold said piston against the plug member 18, as shown, but permitting said piston and its associated parts to be lifted against the compression of said spring.

35 represents a pipe leading to the gasolene tank 36 or other source of fuel supply, and it is conveniently joined to the connection 37 by the member 38', and delivers into the chamber 39, controlled by the check valve 40 associated with the spring 41, said check valve being located between the chamber 39 and the chamber 42, with which the said connection 37 is also provided. Said chamber 42 opens into the nipple 40' of the tubular member 17 as shown, and the width or height of the piston 15 is so chosen as to almost but not quite block the delivery of the fuel from the said chamber 42. Said piston very loosely fits the tubular member 17 so that gasolene or other fuel may readily leak past said piston and occupy the space in said member 17 both above and below said piston 15. The outer tubular member 22 is provided with a plurality of depressions or holes 45 as best shown in Figs. 2 and 4, and the outer casing or casting 1 is provided with an extension 46 into which said member 22 fits, and around which there is conveniently fitted the spring 48 having the detents 49 adapted to engage and disengage said holes 45.

The said casting 1 is further restricted as at 50 so that it makes a substantially close fit with the outer edges of the diaphragm member 26, but said casting is also 5 enlarged as at 51 so that when said diaphragm member 26 is lifted air can readily pass around the rim 50 and into the chamber 51. The upper portion 52 of the said casting is provided on its interior with the 10 hollow curved thimble like piece 53 into which extends the flaring member 31 leaving a restricted passage 54 between said member 53 and said member 31. 55 represents any suitable means rigid with the stem 15 56 of the air throttle 3 by which the said throttle may be operated, and 57 a means connecting the said member 55 with the control mechanism. 60 represents any suitable lever or other means for operating the 20 valve 6, and 61 any suitable connection between said member 60 and the dashboard of a vehicle. 62 represents any suitable connection between the member 60 and the rotatable thumb piece 9 by which when the 25 said member 60 is turned the said thumb piece 9 and tube 10 will also be turned.

The operation of this carburetor will be clear from the foregoing but may be briefly summarized as follows:

30 Ordinarily the valve 6 will not be disturbed and air will be sucked through said valve as well as past the throttle 3 which is not entirely closed. The air passing the valve 6 will be sucked out of the end 12 of 35 the tube 10, will draw fuel from the chamber 14 and mix therewith as it reaches the member 31, where the mixture encounters the air that has been sucked past the almost closed air throttle 3. The parts are so adjusted that the mixture thus produced will 40 be suitable for explosive purposes in starting the engine under ordinary conditions. In cold weather, however, a mixture somewhat richer in fuel is desired, and to obtain 45 it, the valve 6 is partially closed as by turning the lever 60, thus reducing the quantity of air, and at the same time turning the thumb piece 9 through the connection 62, and thereupon turning the tube 10 and 50 screw threads 11 to lower the end 12 and admit more fuel past the said end 12. The screw threads 11 are so pitched as to cause the end 12 of the tube 10 to descend in the tapered chamber 14 the right distance to 55 cause the desired quantity of fuel to be sucked into the passage 4. As the engine is started upon further opening the air throttle 3 additional air may be sucked past said air throttle through the perforations 65 of the 60 diaphragm 26 and into the chamber 29 whence said air will travel through the passage 30 and into the flared member 31 whereupon it will likewise become mixed with any fuel which may be sucked from the 65 tapered space or chamber 14 up through the pipe 13 and into said flared member 31. In adjusting the parts in the first place, the upper end 12 of the tube 10 is adjusted by means of the thumb piece 9 after the plug 18 is screwed home to permit just the right 70 quantity of fuel to be sucked into the passage 4 through the wide open valve 6 for starting the engine under ordinary conditions, and to give the proper mixture when the air throttle is still further opened for 75 running.

In addition to this, it is necessary to provide for the proper leakage of air from the air throttle between the outer rim of the diaphragm 26 and the restricted rim 50. 80 To secure this last named adjustment the member 17 is screwed up into the member 22 by means of the threads 21 until the diaphragm and rim will occupy the proper relative positions when said member 22 is 85 thrust home and held in position by the detents 49.

The parts being in their properly adjusted positions, when the air throttle 3 is opened sufficiently wide the pressure of the 90 air on the under side of the diaphragm 26 will cause said diaphragm together with the tube 13 and piston 15 to be lifted against the compression of the spring 33 whereupon the tapered portion 14 of the tube 13 will 95 widen out around the upper end 12 of the tube 10 and thus permit a larger quantity of fuel to pass into the tube 13 and to become mixed in the flared portion 31 in the passage 4 above said member 31 with the 100 air there present. It will be observed that owing to the shape of the curved surface of the member 53 and to the shape of the flared member 31, after the said flared member 31 lifts through the annular passage 54, said 105 annular passage gradually widens so as to accommodate more and more air along with more and more fuel that will be delivered by the constantly widening tapered space 14.

This lifting of the diaphragm 26 and its 110 associated parts against the compression of the spring 33 will be cushioned to a greater or less extent not only by said spring 33 but also by the fuel which is caught in the tube 17 above said piston 15. Said piston 115 15, however, loosely fits said tube 17 as above stated, and as is indicated in the drawings, so that this said fuel will pass down around said piston 15 and be caught in the chamber 72 above the plug 18. On the other hand, when the air throttle 3 is partially closed and the air pressure on the diaphragm 26 thus relieved the said spring 33 will force said piston 15 down to its position shown in Fig. 2, whereupon the fuel in the space 72 120 125 will pass up around said piston and occupy the space above the same all as will be clear from the drawings.

The check valve 40 being controlled by the spring 41 the fuel tank 36 may be placed 130

as much below or as much above the upper end 12 of the tube 10 as may be desired. That is to say, if it is desired to place the said fuel tank 36 at a lower level than the upper end of said tube 10 or in the position illustrated in Fig. 1, then the spring 41 is adjusted by means of the adjustable nut 75 so that a suction exerted in the passage 4 by the engine will be sufficient to lift said valve 40 to permit the fuel to be sucked into the tapered space 14 as indicated.

On the other hand, if a gravity feed is employed then the member 75 will also be adjusted into such a position as will permit the said fuel to be properly fed when subjected to the combined action of gravity and to the suction above mentioned. It thus results that this carbureter may be run on a gravity feed or on a pure vacuum feed as desired. As a matter of fact it does not depend upon its position or upon gravity for its action at all, but it may be placed on the engine in any suitable and convenient position, and still operate perfectly.

This is an important feature of this invention because it does away entirely with the necessity of employing a float controlled constant level reservoir which is now customary.

In other words, actual practice has proved that notwithstanding the differences in levels of the fuel, in the tank 36, both when gravity aids the suction and when suction alone accomplishes the feeding, yet owing to the valve 40 and the adjustable spring 41 the feeding of the fuel is thoroughly regulated and perfectly satisfactory.

An important feature of this invention resides in the fact that the members 9, 10, 13, 15, 17, 22, 26, and 31 after having been properly adjusted as above disclosed may be readily attached to and detached from the carbureter proper. That is to say, as is well known automobile owners are greatly bothered by having their cars stolen and also by having their own or other chauffeurs using the machines at unauthorized times. As is also well known various locks and other devices have been proposed to prevent these annoyances but in almost every case the unauthorized use of the machine is had in spite of all that can be done.

With this carbureter, however, it is a comparatively simple matter to disconnect the tube 8 at the slip joint 10' to disconnect the connection 37 from the nipple 40' by unscrewing the connection 38, to slip the thumb piece 9 out of the collar 62' and to snap out the detents 49 so that the tube 17, the plug 18, the tube 10 and the diaphragm 26 together with their associated parts are readily withdrawn from the carbureter proper while still in their operative adjusted positions, and to thus disable the car. Not only is the car so thoroughly disabled by this sim-

ple withdrawal of the parts mentioned that it cannot possibly be operated, but the parts withdrawn are so small that they can be readily carried in the pocket; and as the adjustment of the parts are not in the least disturbed it is only a matter of a few seconds to reattach said parts to the carbureter and thus have the car again in condition for operation.

It therefore follows that the owner of a car is at all times by this invention enabled to so fix his car that it can not be used without his authority.

It is obvious that those skilled in the art may vary the details of the construction as well as the arrangement of parts without departing from the spirit of the invention and therefore I do not wish to be limited to the above disclosure except as may be required by the claims.

What I claim is:—

1. In a carbureter the combination of a casing provided with an air inlet and an outlet adapted to be connected to the intake of the engine; an air throttle governing said inlet; a perforated diaphragm governing said outlet; a tubular air connection from said inlet to and through said diaphragm; adjustable fuel controlling means for permitting fuel in predetermined quantities to pass into said tubular connection and connections permitting said fuel controlling means to be readily attached to and detached from said casing in its adjusted position, substantially as described.

2. In a carbureter the combination of a casing provided with an air inlet and an outlet adapted to be connected to the intake of the engine; an air throttle governing said inlet; a perforated diaphragm governing said outlet; a tubular air connection in advance of said throttle from said inlet to and through said diaphragm; a valve controlling said tubular connection; adjustable fuel controlling means comprising a tapered chamber and a movable choking tube in said chamber for permitting fuel in predetermined quantities to pass into said tubular connection, and connections permitting said fuel controlling means to be readily attached to and detached from said casing in its adjusted position, substantially as described.

3. In a carbureter the combination of an outlet adapted to be connected with the intake of an engine; a perforated movable diaphragm controlling said outlet; an internally tapered tube connected with said diaphragm and movable therewith; a piston adapted to cushion the movements of said tube and movable therewith; an adjustable feed controlling tube inside said first named tube adapted to feed air to the latter; an air throttle adapted to admit sufficient air to said diaphragm to lift said piston.

- and first named tube and thereby increase the quantity of fuel passing to the latter, and connections permitting said fuel controlling means to be readily attached to and detached from said casing in its adjusted position, substantially as described. 5
4. In a carbureter the combination of an outlet adapted to be connected with the intake of an engine; a perforated movable dia- 10 phragm controlling said outlet; an internally tapered tube connected with said dia- phragm and movable therewith; a fuel supply; means connecting said supply with said tapered tube; a valve controlling said means; 15 a piston adapted to cushion the movements of said tube and movable therewith; an adjustable fuel controlling means inside said first named tube adapted to feed air to the latter; an air throttle adapted to admit suffi- 20 cient air to said diaphragm to lift said piston and first named tube and thereby increase the quantity of fuel passing to the latter, and connections permitting said fuel controlling means to be readily attached to and detached from said casing in its adjusted position, substantially as described. 25
5. In a carbureter for automobile cars the combination of a tapered fuel feed tube; a fuel feed regulating means inside said tapered tube; means for adjusting said regulating means; and means for readily attaching to and detaching from the carbureter casing said tube and regulating means in their adjusted positions, whereby the carbureter is rendered operative or inoperative, at pleasure, substantially as described. 30
6. In a carbureter the combination of a casing provided with an air inlet and an outlet adapted to be connected to the intake of the engine; an air throttle governing said 40 inlet; a perforated diaphragm governing said outlet; a tubular air connection from said inlet to and through said diaphragm; adjustable fuel controlling means for permitting fuel in predetermined quantities 45 to pass into said tubular connection; a valve controlling said tubular air connection; and means connected with said valve adapted to move said adjustable feed controlling means, substantially as described. 50

In testimony whereof I affix my signature.
EDWARD KNAUSS.
